UNITED STATES PATENT OFFICE.

HERMAN FREDK. NEHR, OF BROOKLYN, NEW YORK, ASSIGNOR TO
BENZIGER BROTHERS, OF NEW YORK, N. Y.

MEANS FOR ATTACHING PINS TO METAL PLATES.

SPECIFICATION forming part of Letters Patent No. 740,305, dated September 29, 1903.

Application filed October 15, 1902. Serial No. 127,361. (No model.)

To all whom it may concern:

Be it known that I, HERMAN FREDK. NEHR, a citizen of the United States, and a resident of the city of New York, borough of Brooklyn, in the county of Kings and State of New York, have invented new and useful Improvements in Means for Attaching Pins to Metal Plates, of which the following is a full, clear, and exact description.

10 This invention relates to improvements in means for attaching pins to metal plates, particularly aluminium plates or badges. As it is difficult or practically impossible to solder metal to aluminium, it is the general practice 15 in making badges or the like of this metal to mechanically secure a brass or similar metal plate in the back of the aluminium plate, and to this brass plate the pin is soldered. Such method requires considerable time and 20 consequently adds to the cost of production. It is the object of my invention to provide a simple means for securing pins to plates without employing solder.

I will describe a means for attaching pins 25 to metal plates embodying my invention, and then point out the novel features in the appended claims.

Reference is to be had to the accompanying drawings, forming a part of this specification, 30 in which similar characters of reference indicate corresponding parts in all the figures.

Figure 1 is a back view of a badge or plate, showing one of the steps of my invention. Fig. 2 is a perspective view of the pin. Fig. 3 is a back view illustrating the badge and 35 pin connected. Fig. 4 is a section on the line 4-4 of Fig. 3, and Fig. 5 shows a slight modification.

Referring to the drawings, 5 designates a

metal plate made in the form of a badge. In 40 the back of the plate is formed a vermicular channel 6 to receive the correspondingly-shaped body or back portion 7 of the pin. By so shaping the parts the pin is held from a laterally-rocking movement. After placing 45 the pin back or body in the channel portions of the metal plate at the sides of the channel are struck up by a suitable tool and bent down upon the back or body, as clearly illustrated in Fig. 3, the lugs being shown 50 at 8.

In Fig. 5 I have shown the channel 9 as having short curves or turns between opposite lugs 10, while in the example first described the channel has a practically straight 55 central portion and the curves appear at the ends.

Having thus described my invention, I claim as new and desire to secure by Letters 60 Patent—

1. The combination with a plate having a channel of irregular form, of a pin having its back or body portion seated in said channel, and means for securing the pin back or body in said channel.

2. The combination with a plate having a vermicular channel, of a pin having its back or body portion conformed to said channel, and lugs at the sides of the channel, and engaged with said back or body portion of the pin.

In testimony whereof I have signed my name to this specification in the presence of two subscribing witnesses.

HERMAN FREDK. NEHR.
